CHARLES A. YOUNG AND GEORGE E. PETERS, OF SPRINGFIELD, AND EDGAR E. PETERS, DECEASED, LATE OF SPRINGFIELD, OHIO, BY GEORGE E. PETERS, ADMINISTRATOR, OF SPRINGFIELD, OHIO

REPEATING FIREARM

Application filed February 27, 1928. Serial No. 257,451.

Our invention relates to repeating firearms of the reciprocating action or pump gun type, and embodies means for increasing the safety and ease of operation, rapidity of action, and improved shell control.

The present construction embodies a longitudinally split breech block, the sections of which are laterally expanded into engagement with abutment shoulders upon the interior walls of the receiver housing when the breech block is in its home position. This affords recoil resistance substantially in dead center relation with the shell and minimizes the material at the top of the receiver, thus facilitating better alignment of the receiver top with the barrel. The gun is made inherently safe by arranging the parts in such a manner that the hammer and firing mechanism can in no way come in contact with the primer of the cartridge until the breech block of the gun is locked in its home position. The firing pin is located between the halves of the breech block and is of somewhat less length. It is partially supported by the breech block and partially supported by a portion of the actuating mechanism for the breech block herein termed the action plate.

The function of the action plate is to withdraw the firing pin from its firing position, 30 retract the hammer back, collapse and expand the breech block at the proper times, provide a support for the secondary shell stop which is also the connector of the action of the gun to the actuating bar on the fore grip. The 35 action plate has the additional function of operating a rocking lever to release the primary shell detent and positively actuating the sear into engaging position. It also supplies an abutment for the recoil lock of the 40 gun.

The hammer necessarily enters between the separated rear portions of the breech block to engage the firing pin which it may do only when the breech block is locked in its final 45 position. The hammer thus locks the breech block sections against disengagement from the abutment shoulders of the receiver and thus acts as a safety device to prevent the gun breech being blown open by the recoil. In 50 other positions of adjustment the retracted

side sections of the breech block extend in the path of the hammer and so prevent its operative engagement with the firing pin.

This construction involves two safety features, to wit: the gun cannot be fired prematurely because the hammer cannot engage in the firing pin until the breech block is locked in home position, and that after the hammer has been released the breech block cannot be collapsed until the hammer is withdrawn from between the two halves of the breech block. This without the aid of other safety devices makes the gun inherently safe.

During the reloading operation the hammer is retracted to an extreme position to permit full movement of the operative parts. Afterwards it is allowed to return to an intermediate "cocked" position from which it falls through shorter range upon release, thus affording quick action and an easy trigger pull. The sear is positively actuated into engagement with the hammer bolt and is locked in such engagement until the reloading mechanism is fully returned to its normal position. The positive actuation of the sear insures engagement of the hammer although the parts may be clogged with burned powder or dirt and thus prevent accidental discharge as the gun is closed. Safety means is provided to temporarily lock the gun against discharge after the operating parts are returned to normal position, which safety device is automatically released by the subsequent retraction of the reloading mechanism or opening of the gun, thereby preventing a balk. To prevent a partially released shell from being re-engaged by the magazine stop upon recoil, the forward or primary magazine stop is controlled by the reloading mechanism and is locked in retracted or inoperative position while the gun is closed and is released only after the breech block has effected a predetermined initial rearward movement. The action slide, associated with the expandable breech block normally travels in unison therewith, but is capable of limited movement independent thereof, by which the breech block is spread and the firing pin positively retracted. The

action bar controlled by the fore grip is de-

tachably engageable with such action slide at any point in its range of movement, the thumb latch for the action bar being duo-functional and acting as a second shell stop.

5 The object of the invention is to simplify the construction, as well as the means and mode of operation of repeating firearms, whereby they will not only be cheapened in construction, but will be more efficient in use, 10 positive in operation, uniform in action, easily operated and unlikely to get out of repair.

A further object of the invention is to provide increased safety of operation by doubly 15 locking the breech block in its "home" position against recoil, and to provide a further safety lock for the hammer action which will prevent discharge of the arm, but which safety device will be automatically released 20 by the actuation of the reloading mechanism.

A further object of the invention is to provide a spring actuated hammer or impeller which is so positioned when "cocked" that it falls through but a limited range of movement, thereby insuring quick response and 25 also affording an easy "trigger pull".

A further object of the invention is to provide means for positively effecting the interengagement of the sear and hammer and 30 for thereafter locking such engaged parts against release until the operating mechanism has been fully returned to its normal or closed position.

A further object of the invention is to provide an improved form of breech block and 35 actuating means therefor, by which the breech block is laterally expanded into locking engagement with the receiver at the forward limit of its movement, and is contracted 40 at the initial rearward movement of the reloading mechanism.

A further object of the invention is to provide improved means for controlling the 45 release of shells or cartridges from the magazine, which shells through inertia of the shell and recoil of the magazine have a tendency to return to the magazine during rapid fire of the gun. To prevent the detention of such a returned shell the primary magazine 50 detent stop is locked in its inoperative position until the gun is opened and the initial shell of the series is removed whereupon the detent is temporarily released for detention of the succeeding shell within the magazine 55 until the gun is again fully closed.

A further object of the invention is to provide increased strength and durability of the operating parts and to render the parts of the mechanism easily accessible for cleaning 60 and replacement and to provide a compact arrangement having minimum number of operating parts.

A further object of the invention is to give 65 positive hammer control and afford a positive means for securing the ejection of the

empty cartridge from the chamber of the barrel and replacing it with a loaded cartridge from the magazine of the gun, and to control the various detents and safety devices by the firing mechanism.

70 With the above primary and other incidental objects in view as will more fully appear in the specification, the invention consists of the features of construction, the parts and combinations thereof and the mode of operation, or their equivalents, as hereinafter described and set forth in the claims.

75 Referring to the accompanying drawings, wherein is shown the preferred, but obviously not necessarily the only form of embodiment of the invention, Fig. 1 is a side view of the assembled gun to illustrate the relative arrangement and proportions of the exteriorly visible parts. Fig. 2 is a bottom view of the assembled gun showing an exterior view of the safety and release features and the relation of the fore grip and action bar with the general gun structure. Figs. 3 and 4 are sectional views through the receiver housing showing the assembled enclosed mechanism in side elevation in both normal or "home" 80 position, and retracted, respectively. Figs. 5 and 6 are similar views observed from the opposite side. Fig. 7 is a top plan view of the same mechanism in its advanced or closed position, the receiver housing being broken away. Fig. 8 is a longitudinal sectional view centrally of the receiver through the action mechanism and breech block. Figs. 9 and 10 are bottom plan views showing the breech block and action slide in closed and open positions respectively. Figs. 11 and 12 are perspective views of the breech block viewed from opposite sides. Fig. 13 is a detail view of the firing pin. Fig. 14 is a bottom plan view of the breech block. Figs. 15 and 16 are perspective views of the action slide in 85 normal and reverse positions respectively. Figs. 17 and 18 are perspective views of the hook end of the action bar. Fig. 19 is a perspective view of the keeper ring in which the breech block sections are pivoted.

90 Like parts are indicated by similar characters of reference throughout the several views.

95 The invention is illustrated as embodied in a take-down, pump type repeating gun which may be either a shotgun or rifle. The gun illustrated is especially designed for use as a shotgun for trapshooting purposes although 100 equally applicable to hunting or other purposes.

105 It will accommodate safely and perfectly all lengths of shells from $2\frac{1}{4}''$ to $3''$ in the 12 gauge size illustrated and all loads that can be 110 safely utilized in such shells. Different loads and different lengths of shells can be intermingled without affecting the operation of the gun. The gun may be made in any size 115

with equal facility to accommodate cartridges of various gauge or caliber.

Referring to the drawings, 1 indicates the stock, 2 the receiver and 3 the barrel of the gun. Beneath the barrel 3 is located the magazine 4 upon which is mounted the fore grip 5 to which is attached the reciprocating action bar 6 projecting rearwardly into the receiver 2. The receiver is provided with a 10 lateral opening 7 through which the spent shell cases are ejected, and is further provided in its bottom with an access opening partially closed by a swinging carrier, through which opening loaded cartridges 15 may be introduced into the magazine 4. The present invention pertains primarily to the mechanism contained within the receiver 2.

Mounted within the receiver 2 for fore and aft reciprocatory movement at the top of 20 the receiver, and in axial alignment with the barrel 3 is a longitudinally split breech block comprising the lateral sections 8—8, which are interconnected at their forward ends for relative swinging movement toward and from 25 each other. To afford a self-contained pivotal connection, the sections 8—8 of the breech block are each formed with a semi-circular stud 9 adjacent to its forward end registering with the like stud of the other section. These 30 registering semi-circular studs 9 are surrounded by an annular groove in which is removably seated a ring block 11 which fits snugly within the annular groove 11' and has a forward flat face portion which registers 35 with the terminal face of the breech block assembly. The top of this ring has two square studs 10 which fit in a groove in the top of the receiver and prevent the ring block from turning out of position.

40 The adjacent faces of the semi-circular pivot studs 9 and forward portions of the block sections 8 have sufficient angular clearance to permit a limited oscillatory movement of the breech block sections 8—8 by 45 which their rearward ends are comparatively widely separated. The interior walls of the receiver 2 are provided with vertical inwardly projecting shoulders 12 into overlapping relation with which the rearward ends of the 50 breech block sections 8 are projected by the lateral expansion or spreading of the split breech block about the pivotal connection of its semi-circular studs 9 within the ring coupling block 11. Located intermediate the sections 8—8 of the breech block and mounted in suitable ways formed in the adjacent faces thereof is a reciprocatory firing pin 13, the reduced forward extremity of which is adapted to be projected beyond the terminal 55 face of the breech block into engagement with a cartridge seated within the chamber of the barrel 3. The rear end of this firing pin 13 is somewhat enlarged and provided with an elongated eye or slot 14. Below the firing 60 pin 13 the breech block sections 8 are provided

on their inner faces with inclined or beveled cam faces 15 and projecting from the under side of each of the breech block sections 8 is a short stud 16. The breech block sections 8 are recessed or cut away as at 17 merely to 70 reduce weight.

The breech block 8 is provided with the usual extractor hooks 18 and 19 overhanging its forward end for engagement with the rim of the cartridge and engaging in the usual grooved guide ways in the inner walls of the receiver 2. The breech block 8 is retracted to and fro in unison with a reciprocatory action plate 20 which is capable of a limited movement in either direction independent of the breech block 8 by which the breech block is contracted preparatory to its rearward movement and is expanded into engagement with the shoulders 12 at the limit of its forward movement. This action slide 20 beneath the breech block reciprocates in guide ways in the inner faces of the receiver walls and is detachably engaged with the reciprocatory action bar 6 for movement in unison with the fore grip 5. The action plate 20 is provided with a duo-functional depressible detent 21 having a dependent finger 22 normally projecting into the path of the shells within the magazine 4 and serving as a secondary shell stop controlling its movement out of the magazine as the breech block moves rearwardly. The detent 21 is also provided with a laterally extending finger having a beveled head 23 for engagement with the hook shaped extremity 24 of the action bar 6. The detent 21 is held in its operative position with the cam head 23 in alignment with the action bar 6 and the depending finger 22 in overhanging relation with the magazine 4 by means of a spring 26 against the tension of which the detent 21 is movable upwardly about its pivotal connection 27. By introducing the finger through the open bottom of the receiver 2 and pressing upwardly upon the depending fingers 22 the beveled head 24 of the detent is raised out of engagement with the action bar 6 thus uncoupling the action bar and plate 20 when it is desired to take down the gun or disconnect the barrel from the stock and receiver. Likewise the detent 21 is actuated against the tension of the spring 26 to permit the introduction of shells through the bottom of the receiver into the magazine 4. The reciprocating plate 20 has side flanges 28 which ride within the corresponding grooved ways in the side walls of the receiver 2. The action plate 20 is further provided with two inclined cam slots 29 into which project the dependent studs 16 carried by the relatively movable sections of the split breech block 8. Upon the rearward movement of the fore grip 5 and with it the reciprocatory action plate 20 the latter will move independently of the breech block 8 to the extent of the cam slots 29. During this rearward independent movement the 125

forward curved ends of the cam slots engage the studs 16 and contract the spread sections of the breech block 8 disengaging them from the shoulders 12, thus enabling the breech block to move rearwardly within the receiver housing 2 in unison with the further movement of the action plate 20. Upon the return or forward movement of the fore grip 5 and with it the action plate 20 the breech block 10 will move in unison therewith until it reaches its forward or home position in which the rear end of the breech block is in registry with the abutment shoulders 12 on the sides of the housing 2. The action plate 20 continues its forward movement after the breech block has come to rest during which the angularly disposed cam slots of the action plate move the studs 16 outwardly thereby spreading the breech block into overlapping engagement with the abutment shoulders 12. This spreading action of the breech block is further assisted by a V shaped cam head 30 projecting intermediate the sections of the split breech block 8 and engaging the cam faces 15 to positively move the breech block sections into interlocking engagement with receiver housing and so hold them during the firing operation. Projected from the top of the cam head 30 is a stud 31 engaging in the elongated slot 14 of the firing pin 13, and acting upon the relative retractive movement of the action plate 20 to also retract the firing pin 13 in relation with the breech block 8.

Upon return movement of the parts the stud 31 stands at the forward end of the slot 14, thus leaving the firing pin 13 free for forward reciprocatory movement under the influence of the hammer.

The action mechanism including the spring 40 actuated hammer, the sear, trigger and safety devices are mounted upon a removable frame block 33 detachably secured in the rear lower portion of the receiver housing. This frame block is shouldered at 34 at its forward end 45 to engage over the lugs projecting from the inner faces of the housing wall and is secured at its rearward end by a screw projecting through the opening 35 and engaging with the end wall of the housing 2. This frame block 33 includes parallel upstanding spaced flanges consisting of forward portions 36 and rearward portions 37. Between the forward portions 36 of such upstanding flanges is pivoted at 38 the swinging hammer 39 actuated by a helical spring 40. This spring 40 surrounds a reciprocatory stem 41 pivoted at 42 to the hammer 39 and extending at its rearward end through a collar 43 having lateral studs 44 engaging the upstanding rear portion 37 of the flanges. The actuating spring 40 abuts upon the collar 43 at its rear end and upon the head 42 of the reciprocatory stem 41 at its forward end. It is placed under compression by the rearward swinging movement of the hammer 39 which is held in

such retracted position by the engagement of a head 45 upon the rear end of the stem 41 with the stop shoulder of the pivoted sear 46. The head 45 is free to move somewhat beyond the stop shoulder of the sear 46 as the hammer 39 is moved to an extreme position as shown in Figs. 4 and 6. However, the normal retracted or cocked position of the hammer 39 is that shown in Figs. 3 and 5 and also in Fig. 8 wherein the detent head 45 is shown in engagement with the sear 46. The trigger 47 which is pivoted to the frame block 33 is provided at its rear end with an upwardly extending finger 48 projecting beneath the sear 46, which upon retraction of the trigger 47 lifts the sear out of engagement with the detent head 45 of the plunger stem 41 thereby releasing the hammer 39. Upon its release the hammer 39 impelled forwardly by the spring 40 enters between the laterally spread rear ends of the breech block 8 and engages the rear extremity of the reciprocatory firing pin 13. If the breech block is not fully home and locked in its advanced position by the spreading of its rear end into overlapping engagement with the abutment shoulders 12, the hammer upon its release will merely engage the terminal face of the breech block 8 which then extends into the path of the hammer until fully separated and the hammer cannot engage the firing pin. This will effectually prevent premature discharge of the gun.

During the firing operation not only is the breech block locked against rearward movement by its engagement with the abutment shoulders 12, but to prevent the gun being opened while in firing condition or too quickly in event of a "hang fire", the action plate 20 is also positively locked by means of stop arms 49 pivoted at 50 to the rearward upwardly projecting portions 37 of the standing flanges upon the frame member 33. These stop arms 49 are normally pressed upwardly by a spring 52 coiled about and having its end engaged with the trunnion stud 38 of the swinging hammer 39. As the hammer 39 is retracted to its cocked position and there beyond by the travel of the action plate 20 and breech block 8 the spring 52 is placed under tension to raise the stop arms 49. However, the arms 49 will not engage the rear end of the plate 20 under the influence of the tension spring 52 until the action plate 20 and breech block are returned to their extreme forward position. As the hammer falls under the influence of the spring 40 upon disengagement of the detent 46 the tension of the spring 52 is released and thereupon the stop arms 49 are automatically depressed out of engagement with the rear end of the action plate 20 by the expansion of a spring 54, interposed between the sear 45 and a rearwardly extending arm 55 of the stop arms 49. The spring 54 has a duo-functional purpose of pressing

the sear 46 into engagement with the detent head 45 and also elevating the rear end 55 of the stop arms 49 whenever the hammer falls and releases the tension of the spring 52.

- 1 It will be understood that the tension of the spring 52 is sufficient when the hammer is raised or cocked to overcome the resistance of the spring 54. The spring 52 thus contributes its influence in holding the sear 46 in engagement with the detent head 45 so long as the hammer is retracted, by holding the stop arms 49 in elevated position, and so placing the spring 54 under increased tension. On the magazine tube 4 between a shoulder 15 on the tube and a shoulder within the fore grip 5 is an expansion spring of short length exerting pressure rearwardly and tending to force the action plate 20 against the stop arms 49. If the hammer falls and the shell in the 20 chamber fails to explode the tension of this expansion spring would be sufficient to make the frictional contact between the arms 49 and plate 20 greater than spring 54 could overcome—therefore the gun could not be 25 opened until fore grip is pushed forward releasing stop arms 49. The explosion of the cartridge in the chamber of the barrel causes a recoil of the whole gun backwards and the inertia of the fore grip automatically 30 presses the expansion spring thereby releasing the arms 49. In case of hang fire the shooter has to push the fore grip forwardly to release the stop arms 49 and as this takes time it prevents the opening of the gun until 35 after the shell has exploded.

The sear 46 is provided at one side with a beveled shoulder 57 engageable beneath a shoulder 58 upon a safety detent arm 59 pivoted at 60. The lower end of this arm 59 40 projects beyond the frame block 33 in the rear of the trigger guard and is manually movable to shift the stop shoulder 58 into and out of overhanging relation with the shoulder 57 of the sear. When so engaged with such 45 shoulder 57 the detent locks the sear in its depressed position and in engagement with the head 45. This prevents the disengagement of the sear and release of the hammer even though the trigger be pulled, until the 50 safety latch has been disengaged. Of course, the safety latch may be released by manual manipulation of the lower projecting end 61. Means is provided, however, for releasing the safety detent 59 automatically upon the 55 opening of the gun. In the event that one tried to discharge the gun with the detent engaged, the hammer and trigger would both be locked and there would be no action of the mechanism whatever. This in trapshoot- 60 ing is not a misfire, but a "balk". Such "balk" does not entitle the shooter to another shot and his failure is counted against him on his score. However, if the hammer falls and the firing pin imprint is impressed 65 upon the shell without exploding it such fail-

ure is termed a misfire and is not counted upon the score against the shooter. In the event of a "balk" or misfire, whichever the failure may be, the natural and logical thing for the shooter is to open the gun and eject 70 the unexploded shell, replacing it with another shell from the magazine preparatory to another shot. In the present case this reloading operation involving the reciprocation of the fore grip 5, the breech block and 75 action plate serve to automatically disengage the safety detent 59, the upper end of which extends forwardly in overhanging relation with the rear arm 55 of the stop arm 59 and into the path of the action plate 20. 80 At the rear extremity of its stroke, the action plate 20 engaging with such forwardly extending extremities of the detent 59 oscillates such detent rearwardly, thus disengaging the stop shoulders 58 and 57 and the gun 85 is ready for firing.

As before stated the release of the hammer 39 relaxes the tension of the spring 52 and permits the stop arm 49 to be depressed out of engagement with the rear ends of the action plate 20 by the reaction of the spring 54. In order to unlock this plate and open the gun when the hammer has not been released, there is provided at the rear end of the arm 55 of the stop arms 49 a dependent 90 L shaped stem 62 pivoted at 63 to the arm 55, the lower end of which projects beyond the frame member 33 adjacent to the extremities 61 of the safety latch. By pressing upon the protruding head of this release stem 62, 100 the arms 55-49 may be oscillated about their pivotal connection against the tension of the spring 52 to disengage them from the rear end of the action plate 20 whereupon the plate 20 and with it the breech block extractor hooks 18 and 19 engaging the rim of the shell the breech block 8 may be retracted. Upon retraction of the breech block, extractor hooks 18 and 19 engaging the rim 105 of the shell pull the shell from the barrel of the gun and, as the breech block continues to move rearwardly, it uncovers an ejector arm 64 mounted in the side wall of the housing 2 and spring actuated inwardly 110 to impel the discharged shell laterally through the opening 7 of the housing. During the retractive movement of the action plate 20 the hammer 39 is engaged by an inclined cam face 39a upon the lower rear side 115 of the cam head 30 carried by the action plate which serves to depress the hammer 39 rearwardly and downwardly to an extreme position shown by dotted lines in Figs. 4 and 6 in which the hammer is depressed below the plane of operation of the plate 20. The hammer is thus moved beyond its normal cocked position shown in Figs. 3, 5 and 8. While the spring 54 will normally project the stop shoulder of the sear 46 into the path of the 120 detent head 45 upon the hammer plunger 125 130

stem 41, means is provided for positively moving the sear into such locking engagement. It sometimes occurs that burnt powder, dirt or grease may accumulate upon the action mechanism to such extent as to prevent a positive and secure engagement of the sear and hammer stem. To prevent any accidental discharge and to insure the positive engagement of the sear there is provided upon the side of the mounting member 33 a rocking lever 65 pivoted at 66. The rear end of the sear 46 is extended laterally at 46' into the path of the rear end of the rocking lever 65. The forward end 68 of the lever 65 is moved into and out of engagement with a shell stop 69 by the oscillation of the lever.

Forwardly of its pivotal connection 66 the lever 65 is provided with a laterally projecting flange or lip 67, which engages in a groove or guide way in the inner face of one of the dependent flanges 28 of the action plate 20 as the latter moves rearwardly. By such engagement of the action plate with the flange or lip 67, the lever 65 is oscillated, thereby depressing its rearward end and raising its forward end 68. The depressed rearward end of the rocking lever 65 engages the lateral extension 47 of the sear 45 positively pressing the sear into locking engagement with the detent head 45. The same movement of the lever 65 raises its forward end 68 from behind the spring pressed primary shell stop 69 to which position it shall have been previously moved by the trigger action in raising the sear at the prior discharge of the gun. As the action plate 20 completes its rearward movement and returns forwardly it rides over the top margin of the rearward arm of the lever 65 thus holding the latter against movement and maintaining the sear in positively locked engagement with the hammer stem until the breech block and action plate have approached their normal home positions.

After the action plate 20 has reached the limit of its stroke the locking lever 65 is free to rise in unison with the movement of the sear 46 under influence of the trigger 47. Consequently as the sear is raised by the trigger the rocking lever is oscillated.

There are two shell stops or detents. One of these, as before described, is the dependent finger 22 carried by the action plate 20. There is in addition a stop lever 69 lying within a slotted recess in the side wall of the housing 2 as shown more particularly in Figs. 5 and 6. This stop lever 69 is pivoted at 70. The forward end of the shell stop lever 69 projects slightly beyond the dependent finger 22 and has an inturned nose or enlargement which is projected into the path of the shells within the magazine 4 by the oscillation of a lever under influence of a spring interposed between the lever and the side of the receiver. This stop arm 69 is

projected upwardly at its forward end into the path of the action slide which is provided with a cam surface 69a by which the detent arm is retracted to allow the rear-most shell or cartridge within the magazine 70 to rest against the secondary detent finger 22. Subsequently it is returned forwardly of the rim of the rearmost shell to intercept the succeeding shell. It will be understood that the shells or cartridges within the magazine 75 4 are pressed rearwardly by a spring plunger in the forward end of the magazine as is usual. When the gun is discharged the recoil carries the gun rearwardly while the inertia of the shells or cartridges retards the movement of the shells, thereby causing them in effect to move forwardly in the magazine 4 away from the detent finger 22. If the primary detent lever 69 was normally positioned in the path of the cartridges upon such forward movement of the shells or cartridges within the magazine 4, the rearmost shell would be engaged and held in its advanced position by the inturned nose of the detent lever 69. However, by maintaining such detent in a retracted or inoperative position and out of the path of the shells at the time of discharge, such shells are free to return rearwardly into engagement with the detent finger 22, after having been projected forwardly in the magazine by the recoil. As the sear is raised to release the hammer 39 the rock lever 65 is also raised at its rear end, thereby depressing the forwardly extending finger 68 which normally lies above the rear end of the shell stop lever 69. When depressed by the rocking of the lever 65 the finger 68 passes behind the rear end of the shell stop lever 69. This engagement of the finger 68 of the rocking lever 65 with the rear end of the lever 69 serves to hold such lever 69 temporarily in inoperative position with its forward nose out of the path of the shells after the action plate starts rearwardly. Thus, at the time of discharge the detent allows the shells free movement in the magazine under the influence of the recoil and afterwards they return with the rear-most shell in engagement with the stop finger 22. As the breech block 8 and action plate 20 move rearwardly the rearmost shell resting against the finger 22 will follow the action plate under the influence of the magazine plunger spring out of the magazine and on to the carrier 71, as shown by dotted lines in Fig. 4. At the same time the movement of the action plate 20 by its engagement with the rocking lever 65 elevates the finger 68 out of engagement with the shell stop lever 69 allowing the forward end of such stop lever to return into the path of the shells in time to prevent the escape of the next succeeding shell from the magazine. At the same time the released rear end of the stop lever 69 is projected beneath the raised fin- 100 105 110 115 120 125 130

ger 68 of the rocking lever 65 thus providing an additional safety lock to prevent oscillation of the lever 65 and release of the sear 46. The swinging carrier 71 is pivoted to the frame member 33 at 72 which happens to be concentric with the pivotal connection 66 of the rocking member 65 on the opposite side of such frame member. There is no connection, however, between the rocking member and the swinging carrier. The forward portion of the swinging carrier is bifurcated to afford two concave fingers upon which the shell is received from the magazine. Each succeeding shell follows the detent finger 22 rearwardly as the action plate 20 and breech block are retracted until arrested by the forward end of the frame member 33 and stop arms 49 which at such time are in their depressed positions as shown in Figs. 3, 5 and 6. The rearwardly extending arm 73 of the swinging carrier 71 carries at its extremity a pivoted cam dog 74 normally projecting into the path of travel of the reciprocating action plate 20. The carrier 71 is normally held depressed with its rearwardly extending arm 73 elevated by a spring 75 coiled about the pivotal stud 72 with one arm engaging the frame member 33 while the other arm extends rearwardly beneath the pivoted cam dog 74. The dog 74 is eccentrically pivoted to the arm 73. This spring 75 is duo-functional in that it yieldingly holds the carrier in depressed position and it simultaneously holds such cam dog in its forward position as shown in Fig. 5. As the action plate 20 approaches the rear limit of its stroke it engages the cam dog 74, and presses such dog rearwardly and downwardly about the pivotal connection with the carrier arm 73, against the tension of the spring 75. This movement is idle. However, as the action plate 20 begins its forward stroke a dependent lug 76 upon said plate engages the top of the cam dog 74 which has been projected in front of said lug by the reaction of the spring 75 as the plate 20 reached the rear limit of its movement. The engagement of said lug 76 with the cam dog tends to throw the dog forwardly to its original position relative to the arm 73 and at the same time depress the dog 74 and with it the arm 73 out of the path of travel of the action plate 20. This is effected without any material increase of tension of the spring 75. During retraction of the breech block this spring is compressed to its maximum degree by the eccentric action of the dog 74. As the dog 74 returns about its pivotal connection which otherwise would relieve the spring tension, the arm 73 is correspondingly depressed thereby maintaining the spring under substantially even tension. This tends to make the action easy as there is no spring resistance to the movement of the carrier to be overcome during the forward stroke. The depression of the cam dog 74 by the dependent lug 76 upon the action plate operates the swinging carrier about its pivotal point thereby elevating the forward end of the carrier. In its upward movement the carrier 71 raises with it the shell which has escaped from the magazine, presenting the shell in an upwardly inclined position as shown in Fig. 4, with the butt of the shell in overlapping relation with the forward face of the breech block 8. As the breech block advances it pushes the elevated shell off the carrier into the chamber of the gun barrel 3. As the shell enters the chamber of the barrel the dependent lug 76 of the action plate passes beyond the cam dog 74 allowing the dog to rise behind the action plate and the swinging carrier to descend to normal position under influence of the spring 75. Upon completion of the forward movement of the breech block the shell is seated in the chamber of the barrel and the breech block and action plate are locked in their home positions as before described. As the breech block and action plate travel forwardly the hammer 39 under influence of springs 40 and 52 follows until detent head 45 strikes the shoulder on sear 46 where it is arrested in the normal cocked position. The sear 46 is still held immovable by the overhanging rear end of the rocking arm 65. When the breech block reaches its home position the action slide is permitted a limited forward independent movement during which cam slots 29-29 acting upon the studs 16 tend to force breech block halves apart into housing 2. This is assisted by the cam head 30 operating against the beveled or inclined cam faces 15 on the inner sides of the halves of the breech block below the firing pin. Just before the action plate 20 reaches its extreme forward position the breech block is fully seated in every respect and the pin can come in contact with the primer, also cam surface 69a strikes magazine stop 69 forcing it out of the path of any case in the magazine, and also unlatching rocking lever 65 so that spring 54 is all that holds the sear 46 in engagement with detent head 45. The gun is then ready for firing, after which the cycle of operation is again repeated.

Instead of engaging the hammer 39 in its extreme position of adjustment shown by dotted lines in Figs. 4 and 6, the hammer is allowed to follow the breech block and action plate in their return movement until arrested in its cocked position as shown in Figs. 3, 5 and 8. From this position it has but a short range of movement into engagement with the firing pin as shown by dotted lines in Fig. 3. This enables quick action of the hammer in engaging the firing pin and minimizes the lapse of time between the pulling of the trigger and the instant of the ham-

mer blow. Moreover, this minimizes the spring tension upon the engagement of the detent head 45 and the stop shoulder of the sear 46. If the hammer was engaged in its 5 extreme position of adjustment the high tension of the spring would tend to resist the disengagement of the sear and detent head 45, thereby making the trigger pull hard.

Assuming the gun to be assembled with the 10 hammer down in fired position, an empty case in the chamber of the barrel and no loaded cases or shells in the magazine of the gun. To insert a loaded case or shell into the magazine 4 the case or shell is thrust 15 against swinging carrier 71 pushing the latter upwardly within the receiver with the gun closed. As the shell enters the receiver it will contact with secondary shell detent 21 which will be pushed upwardly against the 20 tension of the spring 26 about its pivotal connection 27. This opens a path into the magazine 4 of the gun into which the shell can be pushed. After its insertion into the magazine 4, the detent 21 will drop behind 25 the head of case or shell under tension of the spring 26 and retain the case in the magazine. The operation of the gun to replace the spent case in the chamber of the barrel with the loaded shell is secured by pulling 30 the fore grip 5 rearwardly, which in turn transmits motion to receiver mechanism through action bar.

Before opening the gun the breech block is positioned with its two halves expanded 35 at the rear end into recesses in the sides of the receiver, with the rear end of each half overlapping the abutment shoulders 12 in the sides of the receiver. It is prevented from collapsing by studs 16 in the bottom of the 40 breech block which engage with the plate 20 and by the V shaped cam head 30 and the hammer 39, which at such time will project between the sections 8.

When the fore grip is pulled rearwardly 45 cam head stud 31 engaging rear end of firing pin slot 14 pushes firing pin 13 rearwardly. The rear end of the firing pin 13 engages hammer 39 pushing it rearwardly out of slot between halves of breech block 8-8. 50 Simultaneously cam surface 69a moves away from primary stop 69 leaving it free to project into the path of heads of shells coming from magazine. This, however, it cannot do immediately because the rear end of the stop 55 is yet held in position by the end 68 of rocking lever 65. As fore grip pushes the action plate 20 rearwardly the forward ends of cam slots 29 engage the breech block studs 16 and collapse breech block 8-8 so that it is free 60 to travel rearwardly. The action plate 20 and breech block 8-8 will now travel in unison rearwardly pressing hammer 39 back against the tension of its spring, which is placed under compression as the hammer 39 65 swings rearward and is held in a retracted

position by the engagement of the head 45 with the stop shoulder of the pivoted sear 46.

As action slide 20 moves rearwardly a lateral projecting flange or lip 67 engages in a groove or guide way upon the inner face of one of the dependent guide flanges 28 of action plate 20. This engagement raises the forward end and depresses the rear end of rocking lever 65 thereby forcing the sear 46 positively into engagement with the detent head 45. As the forward end of rocking lever 65 is raised it releases the primary case stop 69 which is spring actuated into the path of the end 68 of the rocking lever 65 and locks it in its elevated position. An extension from action plate 20 rides on the rear end from the pivot of rocking lever 65 thereby making an additional safety precaution.

The shell stop 69 is held out of the path of the shells in the magazine until the gun has been opened an appreciable distance since the inertia of the shells in the magazine tube tends to hold them stationary while the whole gun is traveling back with the recoil. This in effect is the same as if the shells traveled forward in the magazine tube. At the same time the inertia of the fore grip tends to unlatch the gun by relieving the rearward pressure on the arms 49 thereby releasing the action. Shooters cannot control this action and it is not desirable to control it because the quicker the sequence of operations necessary to reload the gun can be effected the quicker the next shot is obtainable. Therefore, when the trigger is pulled the sear forces the rocking lever behind the primary shell stop and it is not released until after the gun is cocked on the rearward motion of the action slide. This gives time for the shell coming from the magazine to engage the secondary stop 21 and follow the action slide 20 while the primary stop 69 catches the next shell and prevents the gun from "jamming". Upon return of the action slide the primary stop 69 is pushed out of the path of the rear-most shell in the magazine and it is permitted to fall against stop 21. By permitting the hammer to follow the breech block a portion of its way forward it reduces the length of time required for the hammer to strike the firing pin and arranges the leverage so that the springs impelling the hammer start it without lag.

The sequences of operations as given are accomplished automatically as indicated with each shot fired from the gun and as many shots may be fired consecutively as the capacity of the magazine permits. The speed with which they may be fired depends entirely on the shooter.

From the above description it will be apparent that there is thus provided a device of the character described, possessing the particular features of advantage before enu-

merated as desirable, but which obviously is susceptible of modification in its forms, proportions, and arrangement of parts, without departing from the principle involved or sacrificing any of its advantages.

While in order to comply with the statute the invention is described in language more or less specific as to structural features it is to be understood that the invention is not limited to the specific details shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. In a repeating fire arm the combination with a stock, a barrel and a receiver, of a laterally expansible reciprocating breech block, abutment shoulders upon the inner walls of the receiver with which the breech block effects overlapping engagement when expanded, and actuating means for reciprocating the breech block operating to contract the block out of engagement with said shoulders at the beginning of its rearward movement and effecting the expansion of the block into engagement with such shoulders at the limit of its forward movement.

2. In a repeating fire arm the combination with a stock, a barrel and a receiver, of a laterally expansible reciprocating breech block, abutment shoulders upon the inner walls of the receiver with which the breech block effects overlapping engagement when expanded, said breech block being longitudinally split in a vertical direction to afford two relatively adjustable lateral sections, actuating means for the breech block and means for relatively moving the sections out of and into overlapping relation with the abutment shoulders preparatory to its rearward movement and upon completion of its forward movement respectively.

3. In a repeating fire arm the combination with a stock, a barrel and a receiver, of a laterally expansible reciprocating breech block, abutment shoulders upon the inner walls of the receiver with which the breech block effects overlapping engagement when expanded, said breech block comprising two longitudinal sections pivotally interconnected at their forward ends for limited oscillatory movement in lateral directions into and out of overlapping relation with the abutment shoulders, means for reciprocating the breech block, and means for contracting and expanding the block out of and into abutting relation with the shoulders preparatory to its rearward movement and upon completion of its forward movement.

4. In a repeating fire arm, the combination with a stock, a barrel and a receiver of

a reciprocating breech block longitudinally divided into two relatively adjustable sections, a reciprocating action plate moving in unison with the breech block but capable of a limited movement in opposite directions independent thereof, said plate having wedging engagement with the breech block section, means for reciprocating the breech block and action plate in unison and for giving to the plate a further movement to spread the breech block section for locking the breech block in relation with the receiver and for initially retracting the plate in advance of the retraction of the breech block for unlocking it from the receiver by the relative independent movement of the action plate relative to said breech block.

5. In a repeating fire arm the combination with a stock, a barrel and a receiver of abutment shoulders upon the inner side walls of the receiver, a reciprocating breech block capable of lateral expansion and contraction into and out of abutting relation with said shoulders, a reciprocating action plate moving in unison with the breech block and capable of a limited additional movement independent thereof, means for reciprocating the breech block and action plate and means whereby the relative independent movement of the action plate effects the lateral contraction and expansion of the breech block into and out of engagement with said shoulder.

6. In a repeating fire arm the combination with a stock, a barrel and a receiver, of a longitudinally divided breech block, a firing pin accessible intermediate the sections of the divided block when separated, a hammer engageable with the firing pin when said block is separated, the block extending into the path of the hammer to prevent engagement with the firing pin when the block is contracted, and means for expanding and contracting said block.

7. In a repeating fire arm, the combination with a stock, a barrel and receiver, of a reciprocating breech block, a firing pin carried thereby, a hammer for engagement with said firing pin, said block having a recess into which the hammer enters for engagement with said firing pin, said recess being closed to the hammer action until ready for firing, and means for locking the breech block in engagement with the receiver and simultaneously opening said access recess.

8. In a repeating fire arm, a stock, a barrel and a receiver, a longitudinally split reciprocating breech block in the receiver, a firing pin enclosed between the sections of said breech block, a hammer entering between the sections of said block when separated into engagement with the firing pin, and means for opening and closing the breech block whereby the hammer will be excluded from access to the firing pin when the block is closed.

9. In a fire arm, the combination with a stock, a barrel and a receiver, of a reciprocatory breech block, a firing pin therein, a hammer entering within an access opening in the rear of the block for engagement with the firing pin, means for reciprocating the breech block, and means for opening and closing the access opening in said block in accordance with the movement of the block whereby the recess will be opened and the firing pin accessible to the hammer only when the block is in its "home" position.

10. In a fire arm the combination with a stock, a barrel and a receiver of a laterally expandible and contractible reciprocatory breech block, a firing pin enclosed therein, a hammer entering a recess on the breech block for engagement with the firing pin when the block is spread, stop shoulders on the receiver, with which the block has abutting engagement when spread, and means for spreading said expandible block to engage it with said shoulders and open the recess for the entrance of the hammer and for contracting the block to disengage it from the receiver and close the recess to exclude the hammer.

11. In a fire arm the combination with a stock, a barrel and a receiver, of a reciprocatory breech block, longitudinally divided in a vertical plane into two relatively adjustable sections, substantially semi-cylindrical studs formed on the respective sections and in registry with each other, said block sections being recessed about said studs, a collar seated in said recesses and surrounding the studs to hold said relative movable sections in pivotally adjustable relation, means for reciprocating the breech block, and means for expanding the breech block into locking engagement with the receiver at the completion of its forward movement and for contracting the breech block preparatory to its rearward movement.

12. In a fire arm the combination with a stock, a barrel and of firing mechanism including a reciprocatory breech block, longitudinally divided in a vertical plane into two relatively movable sections, a firing pin of less length than the divided breech block enclosed therebetween, the extremities of the breech block sections projecting into the path of the hammer beyond the extremity of the firing pin when said divided block is contracted, means for reciprocating the breech block and means for shifting the breech block sections laterally out of the path of the hammer when in its firing position to permit the entrance of the hammer therebetween into engagement with the firing pin.

13. In a fire arm the combination with a stock, a barrel and of firing mechanism including a reciprocatory breech block, longitudinally divided in a vertical plane into two relatively adjustable sections, a reciprocatory

action plate common to the breech block sections, and capable of limited to and fro motion independent of the breech block, actuating means for the action plate and cam means operatively connecting the plate and breech block sections whereby the movement of the action plate relative to the breech block serves to spread and retract the relatively adjustable sections of the divided block.

14. In a firearm the combination with a stock, a barrel and of firing mechanism including a reciprocatory breech block, a reciprocatory firing pin within the breech block, a reciprocatory action plate capable of limited to and fro motion independent of the breech block, an operative connection between the action plate and firing pin whereby the independent movement of the action plate effects the retraction of the firing pin, said pin being capable of operative movement under influence of the hammer independent of the action plate when the action plate and breech block are in their firing positions.

15. In a repeating fire arm, the combination with a stock, a barrel and firing mechanism including a reciprocatory breech block, a hammer and a sear of a manually operable safety lock for preventing the release of the hammer and means for disengaging the safety lock upon reciprocation of the breech block.

16. In a fire arm the combination with a stock and barrel of firing mechanism including a hammer and a reciprocating breech block, means for actuating the breech block, a manually engaged safety lock for said hammer for preventing its release, and means for automatically disengaging the safety lock by the operation of the breech block reciprocating means.

17. In a repeating fire arm, the combination with a stock, a barrel and firing mechanism including a reciprocatory breech block, a hammer and a sear, and a magazine for shells, of a shell stop, a rocking lever the rear end of which has operative engagement with the sear and the forward end of which has operative engagement with the shell stop, said lever being oscillated upon the rearward movement of the breech block to lock the sear in its engagement with the hammer and to so hold it until the breech block approaches its firing position during its return movement, and to simultaneously permit the shell stop to move into operative position to arrest the escape of shells from the magazine by the movement of the forward end of said rocking lever.

18. In a repeating fire arm, the combination with a stock, a barrel and firing mechanism including a reciprocating breech block, a hammer and a sear, of manually operated means for locking the sear in engagement with the hammer, said locking means being held in operative engagement with the sear

during the to and fro movement of the breech block and automatically released only as the breech block approaches its forward limit of its movement.

- 5 19. In a repeating fire arm, the combination with a stock, a barrel and firing mechanism including a reciprocating breech block, a hammer and a sear, a locking arm into the path of which the sear projects, means for
- 10 rocking said arm upon the rearward movement of the breech block to positively move the sear into engagement with the hammer, said locking arm being held in its operated position until the breech block approaches
- 15 the limit of its return movement.
- 20 20. In a repeating fire arm, the combination with a stock, a barrel, a magazine and firing mechanism, of a reciprocatory breech block, a reciprocatory action bar for moving
- 25 the breech block to and fro, a latch member for detachably coupling the action bar with the breech block, a primary shell detent and a secondary shell detent for arresting the shell when released from the magazine by the
- 30 withdrawal of the primary detent, said secondary detent being fixedly connected with such latch member for which the second detent forms a finger trip for disengaging the latch member from the action bar.
- 35 21. In a fire arm of the character described, the combination with a stock, a barrel and firing mechanism including a reciprocatory breech block, a locking member for holding the breech in firing position, a trigger and a
- 40 sear, and a spring common to the sear and breech block locking member tending to hold the sear in hammer-holding position and acting to disengage the breech block holding member upon release of the hammer.
- 45 22. In a fire arm the combination with a stock, a barrel and firing mechanism of a safety lock for preventing discharge of the fire arm, said safety lock being manually adjustable both into and out of locking position, said lock being automatically disengageable by the retraction of the firing mechanism independent of its manual adjustment.
- 50 23. In a fire arm the combination with a stock, a barrel and firing mechanism, of a safety lock for preventing discharge of the fire arm, manually operable means for disengaging the safety lock by the opening of the fire arm, said manual and automatic release means being independently operable.
- 55 55. In testimony whereof, we have hereunto set our hands.
- CHARLES A. YOUNG.
GEORGE E. PETERS.
GEORGE E. PETERS,
60 *Administrator of the Estate of Edgar E.
Peters, Deceased.*
